STRIP FOLDER

Albert A. Ackerman, South Bend, Ind., assignor to
 The Singer Manufacturing Company, Elizabeth,
 N. J., a corporation of New Jersey

Application April 10, 1937, Serial No. 136,071

17 Claims. (Cl. 112—147)

This invention relates to improvements in strip-folding attachments for use more particularly in connection with sewing machines and has for its primary object to facilitate the production 5 of straps, belt-loops and kindred articles from strips of material.

The present invention also aims to provide a folder of simple and compact form for inturning the side edges of superposed strips of material.

With the foregoing and other objects in view, as will hereinafter appear, the invention consists in the construction and arrangement of the parts of the strip-folder described in connection with 15 the accompanying drawing, which illustrates a preferred embodiment of the invention and in which:

Fig. 1 represents a vertical and substantially central longitudinal section of the strip-folder, together with a transverse section of the bed-plate of a sewing machine to which the strip-folder is applied. Fig. 2 represents a top plan view of the strip-folder and a portion of the 20 sewing machine bed-plate and presser-foot, and illustrates the work in the finishing operation to form a strap. Fig. 3 represents, in perspective, the individual casing and arbor units of the strip-folder. Fig. 4 represents a transverse section of the strip-folder substantially on the line 4—4 of Fig. 2. Fig. 5 illustrates, in perspective, the end 25 portions of the superposed strips as initially secured together. Fig. 6 illustrates, in perspective and partly in section, the end portion of the strap in the finishing operation. Fig. 7 represents a transverse section of the finished strap intermediate the ends thereof.

Referring to the drawing, the improved strip-folder is illustrated as applied to a sewing machine having a bed-plate 1 provided with a throat-plate 2. Operating through said throat-plate 2 is a feed-dog 3 which may be actuated in any usual or suitable manner to advance the work. Opposed to the feed-dog 3 is a presser-foot 4 carried by the lower end of a presser-bar 5, the presser-foot being provided with needle-slots 6 spaced transversely of the line of feed. A vertically reciprocating needle-bar 7 carries at its lower end a pair of needles 8 (only one of which is shown), arranged abreast with respect 45 to the direction of feed of the work and cooperating below the throat-plate 2 with any usual or suitable complementary stitch-forming mechanism (not shown).

The improved strip-folder has at one side 50 thereof a supporting shank 9 formed with slots

10 to receive the folder securing screws 11 which, in the present instance, are threaded into the front slide-plate 12 of the bed-plate 1. Carried by the folder-shank 9 is a primary folder-section or casing unit comprising a tubular casing 13, 5 preferably although not necessarily rectangular in cross-section. As illustrated in the drawing, the tubular casing 13 has a top wall 14, a bottom wall 15 and opposed side walls 16, said walls being tapered to define a tubular passageway 10 constricted toward the delivery end of the folder. Projecting inwardly from each of the side walls 16 is a fold-edge turning lip 17 disposed substantially midway between the top and bottom casing-walls, the lips 17 being spaced from each 15 other and preferably extending from adjacent the front end of the tubular casing to the delivery end thereof. The upper and lower faces of the lips 17 preferably merge concavely into the respective side walls 16, thereby providing a plurality of opposed curved guiding walls adapted to inturn the edges of superposed strips of material.

The bottom wall 15 of the tubular casing 13 has a forward extension 15' which forms the bottom 20 of a trough having substantially parallel up-standing side walls 16' extending forwardly from the casing side walls 16, the side edges of the trough-bottom 15' being spaced from the side walls 16, to define therebetween substantially 25 parallel slots 18. The forward end of the trough bottom wall 15' is bent under and is soldered or otherwise suitably secured to a cross-bar 19 connecting the side walls 16'. Adjacent the front 30 end of the tubular casing 13, the trough side walls 16' are each provided with upwardly open notches 35 20.

Complemental to the primary folder-section above described is an auxiliary folder-section or arbor unit 21, comprising a block 22 of which the 40 side walls, adjacent one end of the block are provided with flanges 23 forming spaced strip-guiding ears extending above and below the upper and lower faces of the block. Projecting outwardly from the block-flanges 23 are oppositely directed 45 pins 24 adapted to be removably seated in the primary folder-section notches 20, thereby to support the block 22 within the tubular casing 13 with the upper and lower faces of the block 50 spaced from the top and bottom walls, respectively, of said casing. When thus assembled, the lower ears or flanges 23 extend into the primary folder-section slots 18 at the rearward ends of said slots and thereby serve to locate as well as to steady the block 22.

Extending rearwardly from the upper and lower faces of the block 22, toward the delivery end of the folder, are preferably substantially flat tongues or arbors 25 and 26 tapered toward the free ends thereof. The arbors are spaced from each other so that, in the operative position thereof, the upper arbor 25 is disposed above and the lower arbor 26 below the plane of the casing lips 17. The upper arbor 25 has its free end terminating substantially at the delivery end of the tubular casing 13, while the lower arbor 26 has a reduced and preferably narrowed extension or finger 27 which in its operative position underlies the presser-foot 4 within the field of action of the feed-dog 3. The presser-foot 4 is preferably provided in its work-engaging face with a clearance groove 28 for said finger 27. The side edges of the arbors 25 and 26 are spaced from the side walls 16 of the casing 13 and are complementary to the inner concave faces of said casing, above and below the casing-lips 17, in inturning the side edges of superposed strips of material.

In the formation of straps and similar articles made from superposed strips of material with inturned side edges, difficulty has been experienced in finishing the ends of the straps in a manner such that the ends of the strips are also inturned and secured by stitches. In accordance with the present improvement, the end portions of superposed strips A and B are first secured together by a single line of stitches S, conforming to the desired shape of the strap-end when finished, as illustrated in Fig. 5 of the drawing. The ends of the strips beyond the seam may be snipped off to remove surplus material, and the strips are then reversed, i. e., the stitched strips are turned inside out, thereby to inturn the joined ends of the strips, as illustrated in Fig. 6.

The arbor-unit 21 is withdrawn endwise from the casing-unit 13 and the two arbors 25, 26 are inserted between the reversed strips A and B, until the arbor-finger 27 engages the previously closed end of the strips. One of the strips, as A, is thus disposed flatwise upon the arbor 25 and between the upper of the strip-guiding ears 23, while the other strip B is disposed flatwise below the arbor 26 and between the lower of the ears 23. The arbor unit 21, thus loaded, is then inserted arbor-end first into the casing-unit 13 to seat the supporting pins 24 in the side-wall notches 20, and the lower ends of the ears 23 in the slots 18. By suitably spacing from each other the opposed lips 17 of the casing 13, the requisite clearance is afforded for operatively positioning the loaded arbor-unit.

Inasmuch as the finger 27 in its operative position underlies the presser-foot 4, it will be understood that the act of assembling the primary and loaded auxiliary folder-sections serves also to position the previously closed end of the work under the presser-foot. By now placing the sewing machine in operation, the feed-dog 3 engages the lower ply of the work-strips and feeds said strips off from the arbor-finger 27, thereby drawing the strips through the strip-folder. The margins of the strips are thereby bent by the lips 17 about the side-edges of the arbors 25 and 26, as will be readily understood, and the superposed, inturned side-edges of the strips are advanced to the needles 8 to receive the stitches S' and S'', thereby to secure said inturned side edges.

It will be noted that the auxiliary folder-section pins 24 are guided into the notches 20 by the upper edges of the trough side-walls 16. Consequently, the auxiliary folder-section 21 need only be inserted into the primary folder section 5 sufficiently to enable the feed-dog 4 to engage and advance the work, whereby if desired the stitches S', S'' may be started substantially from the end of the strap. As the stitching progresses, the auxiliary folder-section is then advanced into 10 its normal operative position.

Having thus set forth the nature of the invention, what I claim herein is:

1. A strip-folder for sewing machines, comprising, a longitudinally-tapered tubular casing having opposite side walls provided interiorly of the casing with opposed lips, arbors disposed within said casing above and below said lips and extending longitudinally of the casing in spaced relation to said side walls, and supporting means 20 for said arbors.

2. A strip-folder for sewing machines, comprising, a tubular casing having opposite side walls provided interiorly of the casing and substantially medianly of the width of said side walls with 25 opposed fold-edge turning lips, strip-separating arbors disposed within said casing in spaced relation to said side walls above and below the plane of said lips, and supporting means for said arbors.

3. A strip-folder for sewing machines, comprising, a tubular casing having side walls each provided interiorly of the casing with a fold-edge turning lip merging concavely at opposite sides 35 thereof into the inner face of the respective casing side wall, substantially flat arbors disposed within said casing with their side edges spaced from the casing side walls above and below said lips, and supporting means for said arbors.

4. A sewing machine strip-folder having opposite side walls each provided lengthwise thereof with a fold-edge turning lip having its opposite faces merging concavely into the proximate faces of said side walls, arbors having opposite side edges coacting with said lips and said side walls at opposite sides of said lips in inturning the margins of superposed strips of material, strip-guiding walls confining said strips to flatwise engage said arbors, and supporting means 40 for said arbors.

5. A sewing machine strip-folder having tapered side walls provided lengthwise thereof with inwardly directed and opposed fold-edge turning lips, substantially flat strip-separating arbors having their side edges respectively disposed at opposite sides of said lips in spaced relation to said side walls, strip-confining folder-walls disposed adjacent the outer faces of said arbors, one of said arbors having a rearward extension of reduced width projecting beyond the work-delivery end of said walls, and supporting means 60 providing for shifting said arbors endwise as a unit, relatively to said walls, from and into operative position.

6. A strip-folder for sewing machines, comprising, a longitudinally-tapered tubular casing having opposite side walls provided interiorly of said casing with opposed lips, arbors complementary to said side walls and lips in inturning the side edges of superposed strips of material, 70 said arbors being disposed within said casing and extending longitudinally thereof in spaced relation to said side walls above and below said lips, and means for detachably supporting said arbors upon said side walls.

7. A strip-folder for sewing machines, comprising, a longitudinally-tapered tubular casing having side walls provided with inwardly directed and opposed lips, said side walls having forward extensions each provided with an upwardly open notch, arbors disposed within said casing and extending longitudinally thereof in spaced relation to said side walls above and below said lips, a spacing block connecting the forward ends of said arbors, and oppositely directed pins projecting from said spacing block and adapted to be seated detachably in said notches, thereby to support said arbors.

8. A strip-folder for sewing machines, comprising, a tubular casing having its side and bottom walls extending forwardly from the tubular portion thereof to form an upwardly open trough, said side walls within the tubular portion of the casing having inwardly directed and opposed fold-edge turning lips, an arbor-carrying block adapted to be detachably supported upon the side walls of said trough, and substantially flat arbors extending from said block into said tubular casing with the side edges of said arbors spaced from the side walls of said casing above and below said lips.

9. A strip-folder for sewing machines, comprising, a longitudinally-tapered tubular casing having side walls provided with inwardly directed and opposed lips, an upwardly open trough having substantially parallel side walls and a bottom wall in substantial alignment with the side and bottom walls, respectively, of said casing, the trough side walls each having an upwardly open notch and the trough bottom wall being provided with substantially parallel slots extending longitudinally of said trough, an arbor-carrying block provided with oppositely directed pins adapted to be removably seated in said side wall notches, said block having spaced depending flanges adapted to enter the trough bottom wall slots, and substantially flat arbors adapted to extend from said block into said tubular casing with the side edges of said arbors spaced from the side walls of the casing above and below the casing lips.

10. A strip-folder for sewing machines, comprising, a tubular casing having side walls each provided with an inwardly directed lip spaced from the lip of the other side wall, an upwardly open trough having substantially parallel side walls and a bottom wall in substantial alignment with the side and bottom walls, respectively, of said casing, an arbor unit providing strip-guiding faces with side edges adapted to extend longitudinally of said casing at opposite sides of said casing side-wall lips, a finger extending from said arbor unit beyond the work-delivery end of said casing, and means for removably supporting said arbor unit upon the side walls of said trough.

11. In a sewing machine, the combination with work-feeding mechanism and stitch-forming mechanism including a pair of reciprocatory needles spaced crosswise of the line of feed, of a strip-folder disposed in front of said needles comprising complementary casing and arbor units adapted to inturn the side edges of superposed strips of material, said arbor unit being separable

from said casing unit and having a finger extending, in the operative position thereof, beyond the delivery end of said casing unit and into the field of action of said feeding mechanism.

12. A strip-folder for sewing machines, comprising, separable casing and arbor units providing complementary edge-folding means arranged to inturn the side edges of superposed strips of material between said strips, said arbor unit including flatwise superposed arbors providing vertically spaced fold-defining members within said casing adjacent each of the opposed side walls thereof.

13. A strip-folder for sewing machines, comprising, a casing providing a plurality of opposed edge-turning walls, a plurality of arbors disposed within said casing and complementary to said walls in inturning the side edges of superposed strips of material between said strips, one of said arbors having a finger projecting beyond the work-delivery end of said casing, and supporting means providing for removing said arbors endwise from said casing.

14. A sewing machine strip-folder having opposite side walls each provided lengthwise thereof with a fold-edge turning lip, said lips being spaced from and directed toward each other, arbors disposed between said side-walls and complementary to said side walls and lips in inturning the side edges of superposed strips of material between said strips, strip-confining folder-walls disposed adjacent the outer faces of said arbors, and supporting means providing for withdrawing said arbors endwise from between said side walls.

15. A sewing machine strip-folder having opposite side walls each provided lengthwise thereof with a fold-edge turning lip directed toward the lip of the opposite side wall, substantially flat strip-separating arbors disposed at opposite sides of said lips and widthwise extending from adjacent one of said side walls to adjacent the other side wall, strip-confining folder-walls disposed adjacent the relatively remote faces of said arbors, and supporting means providing for shifting said arbors endwise as a unit and relatively to said side walls from and into operative position.

16. A strip-folder for sewing machines, comprising, a longitudinally tapered tubular casing having side walls each provided interiorly of the casing with a fold-edge turning lip opposed to the lip of the opposite side wall, and substantially flat arbors within said casing complementary to said side walls and lips in inturning the side edges of superposed strips of material between said strips, one of said arbors having an extension projecting beyond the work-delivery end of said casing.

17. A strip-folder for sewing machines adapted to inturn the side edges of superposed strips of material between said strips, comprising a tubular casing having opposed edge-turning walls, and flat-wise superposed arbors disposed within said casing and providing a pair of vertically spaced side edges complementary to each of said edge-turning walls.

ALBERT A. ACKERMAN.
